UNITED STATES PATENT OFFICE.

LOGAN SMITH, OF OAKLEY, ILLINOIS, ASSIGNOR TO EDDIE E. SMITH, OF DECATUR, ILLINOIS.

WRENCH.

1,196,039.

Specification of Letters Patent. Patented Aug. 29, 1916.

Application filed February 5, 1916. Serial No. 76,434.

To all whom it may concern:

Be it known that I, LOGAN SMITH, a citizen of the United States, residing at Oakley, in the county of Macon and State of Illinois, have invented certain new and useful Improvements in Wrenches; and I do hereby declare the following to be a full, clear, and exact description of the invention, such as will enable others skilled in the art to 10 which it appertains to make and use the same.

This invention comprehends certain new and useful improvements in wrenches and has for its primary object to provide a device of this character which will be of extremely simple construction and operation as well as cheap to manufacture and highly efficient in use.

The invention has for another object to 20 provide a device of this character in which the pawl for engagement with the rack teeth and the shank of the tool may be resiliently retained in operative position by means of a leaf spring which has one end secured in the forward portion of the movable jaw, one end of the pawl projecting from the front face of the movable jaw for engagement by the operator's finger to disengage the nose of the pawl from the rack 25 teeth and swinging said pawl upon its pivot against the tension of the leaf spring.

The invention has for a further object to provide a wrench of this character which will be constructed in such manner that it 35 may be readily and easily operated and should any of the parts become worn or broken, they may be readily replaced at small cost.

With these and other objects in view as 40 will become more apparent as the description proceeds, the invention consists in certain novel features of construction, combination and arrangement of parts as will be hereinafter more fully described and 45 claimed.

For a complete understanding of my invention, reference is to be had to the following description and accompanying drawings, in which—

50 Figure 1 is an elevation of my improved wrench with parts in section, and Fig. 2 is a detail transverse section on the plane of line 2—2 of Fig. 1.

Referring in detail to the drawings by 55 numerals, 1 designates the shank having the

handle members 2 secured on its one end and the regular stationary jaw 3 mounted upon its opposite end, while the rack teeth 5 are formed on the front face of said shank 1 for a limited distance from the handle members 2.

Slidably mounted for longitudinal movement upon the shank 1 is a movable jaw 6 which has its front side open, as shown at 7, and a pawl 8 mounted therein and adapted to swing upon the pivot pin 9 which extends transversely through the front portion of said jaw 6. The pawl 8, when in its engaging position, has its nose 10 engaged with the rack teeth 5, previously mentioned. The pawl 8 is resiliently retained in its engaging position by means of a spring 11 which has its inner end engaged against the shoulder 12 formed at the enlarged end of said pawl 8, adjacent the pivot pin 9 for said pawl 8. The leaf spring 11 may be moved longitudinally through the opening 13 in the gripping portion of said movable jaw 6, said slot 13 being inclined to place the leaf spring 11 at the proper 20 incline, as will be readily understood by referring to the drawings. The leaf spring 11 is held in position by means of a screw 14 or the like secured in the side of the movable jaw 6 abutting the handle and engaged 25 through said leaf spring 11, the head of said screw 14 being flush with the face of the jaw 6 sliding upon the smooth portion of the front face of the shank 1, as will be readily understood by referring to the drawings, thereby making it impossible for the screw 14 to work loose or the spring 11 to move in either direction, or be removed 30 without first removing the movable jaw 6 and then removing or loosening the screw 14. This assures the spring 11 being held 35 in proper position and at the same time making it possible for said spring to be readily replaced, when desired, which is a great advantage as all springs in tools of 40 this character frequently become ineffective or break, making it necessary to replace the same, to restore the tool to proper condition and efficiency.

While I have shown and described the 45 preferred embodiment of my invention, it will be understood that minor changes in the details of construction, combination and arrangement of parts may be made without departing from the spirit and scope of the 50 invention.

invention as claimed or sacrificing any of the advantages thereof.

What is claimed is:—

A wrench comprising a shank, a stationary jaw on one end of said shank, a handle formed on the opposite end of said shank, said shank provided with rack teeth on one edge, a movable jaw slidably mounted upon said shank and having a recess formed in 10 one face, a pawl mounted in said recess, its nose normally engaged with said teeth, a flat leaf spring rigidly secured by one of its ends in one wall of said movable jaw and having its opposite end extending into said 15 recess for engagement against the inner side

of said pawl to retain the nose of the latter in engagement with the teeth, and a fastening member secured in said jaw and extending through said spring to rigidly retain the latter against movement, the head 20 of said securing member abutting said shank and preventing any outward movement of the same.

In testimony whereof I affix my signature in presence of two witnesses.

LOGAN SMITH.
